UNITED STATES PATENT OFFICE.

GEORGE H. GILMAN, OF CLAREMONT, NEW HAMPSHIRE, ASSIGNEE TO SULLIVAN MACHINERY COMPANY, A CORPORATION OF MASSACHUSETTS.

MOTOR.

Application filed May 5, 1919. Serial No. 295,014.

- My invention relates to motors and more especially though not exclusively to pressure fluid motors for use in mining, quarrying or the like.
- 5 It has for its object to provide an improved pressure fluid motor. A further object of my invention is to provide an improved, compact, light, and powerful construction adapted to increase materially the cutting speed 10 of the tool, and at the same time, efficiently lubricate the moving parts of the motor. A still further object of my invention is to provide an improved motor having an improved tool rotating mechanism which may be made 15 operative or inoperative at the will of the operator, to rotate the tool. Other objects and advantages of my improved construction will, however, hereinafter more fully appear.
- 20 In the accompanying drawings I have shown for purposes of illustration two embodiments which my invention may assume in practice.
- In these drawings,—
- 25 Fig. 1 is a longitudinal, sectional view taken on the line 1—1 of Fig. 3, of my improved motor, some of the parts being shown in side elevation.
- Fig. 2 is a longitudinal, sectional view 30 thereof on the line 2—2 of Figs. 1 and 3.
- Fig. 3 is an end view of my improved motor.
- Fig. 4 is a transverse, sectional view taken on line 4—4 of Figs. 1 and 2.
- 35 Fig. 5 is a longitudinal, sectional, detail view taken substantially on the line 5—5 of Figs. 3 and 9.
- Fig. 6 is a longitudinal sectional view of the cylinder taken on line 6—6 of Fig. 3.
- 40 Fig. 7 is another longitudinal sectional view of the cylinder taken on line 7—7 of Fig. 3.
- Fig. 8 is a transverse sectional view taken on the line 8—8 of Figs. 1 and 2.
- 45 Fig. 9 is a transverse sectional view taken on the line 9—9 of Figs. 1 and 2.
- Fig. 10 is a transverse sectional view taken on the line 10—10 of Figs. 1 and 2.
- 50 Fig. 11 is a longitudinal sectional view taken substantially on the line 11—11 of Fig. 3 showing the clutch controlling mechanism.
- Fig. 12 is a side elevation of a part of the rotating mechanism.
- Fig. 13 is a transverse sectional view of the tool chuck taken on the line 13—13 of Fig. 1.
- Fig. 14 is another transverse sectional view of the tool chuck taken on the line 14—14 of Fig. 1.
- Fig. 15 is a longitudinal sectional view taken substantially on the line 11—11 of Fig. 3 showing the modified clutch controlling mechanism.
- In this illustrative construction, it will be observed that I have shown a motor cylinder 1, which preferably has a substantially elliptical shape throughout a part of its length as shown in Fig. 10 and which has a cylinder, or chamber 2, and a plurality of longitudinally extending side chambers 3 and 4. The forward end of the cylinder is partially closed by a buffer ring 5 against which abuts a chuck housing 6. This chuck housing encloses a chuck 7 and a locking ring 8, the chuck 7 being preferably mounted to rotate within the chuck housing 6. This chuck 7 is adapted to receive a steel 9 having lugs 10 formed thereon, the steel 9 shown being preferably of the hollow type, having an axial bore 11 extending therethrough.
- The opposite or rear end of the cylinder is 80 preferably partially closed by an end plate 12 carrying a head block 13 on which is preferably mounted a controlling valve 14 with its controlling handle 14' for controlling the flow of pressure fluid from the pipe line 15 to the various parts of the motor. I preferably mount on the head block 13 a boss 16, to be hereinafter more fully described, having communication with a water tube 17 which is shown as attached to the boss by a threaded nipple 18 and a nut 19, although any other of a number of well known connections may be used if desired.
- The parts of the tool so far described comprising the chuck 6 and the head block 13 and the various members therebetween are 85 preferably held rigidly together by a plurality of side rods 20 and 21 which preferably pass longitudinally through these tool elements and are adapted to receive nuts 22, 23 and split rings or washers 24, 25. In the form shown, the side rod 20 preferably passes through a sleeve 26 in the side chamber 4, the sleeve 26 being in my preferred form carried by bushings or hollow dowel pins 27, 28 to 90 which the sleeve is attached by swaging as is shown at 29. These dowel pins serve the plurality of functions of retaining the sleeve

26 in proper position, of closing the ends of the aperture 4 so as to form an air-tight chamber therein, and to keep the different elements of the motor from transverse or rotative displacement relative to each other. The side rod 21 is preferably passed through a part of the rotating mechanism to be hereinafter more fully described.

The motor comprising the cylinder 1 and 10 the parts attached thereto is preferably mounted so that it may be moved toward the work during the drilling operation or that it may be retracted to replace the steels, by a cradle 30 in which is rotatively mounted a feeding screw 31 operating in a non-rotative nut 32 preferably attached to the cylinder 1, a handle 33 being provided on the outer end of the feed screw 31 by means of which the motor may be moved as desired. As the tool 15 is thus fed toward the work, a piston 34 mounted to reciprocate in the cylinder chamber 2 under the influence of pressure fluid admitted alternately to the opposite ends of the cylinder is operated to drive a drill steel. 20 This piston is preferably spooled out near the center thereof to form an annular recess 35 which cooperates with ports and passages hereinafter to be described, to regulate the flow of fluid to the cylinder. On the forward 25 end of the piston there is formed, in the preferred form of my invention, a forwardly projecting striking head 36 adapted to pass through a recess 37 in the buffer ring 5 and contact with the shank end of the drill steel 30 to force the latter against the work. To prevent the compression of air in this aperture 37, which compression may result in the forcing of the chuck into binding relation with the chuck housing, I preferably provide 35 an annular recess 38 in the buffer ring and vent this recess to the atmosphere by a port 39, although as is obvious, other means may be used to prevent the formation of a high pressure in the buffer ring or the chuck housing.

When it is desired to operate the pneumatic tool to drive a drill steel, the hollow interior 40 of the controlling valve 14 may be placed in communication, by means of 40 ports 41, 42, with either or both of two passageways 43, 44 to conduct pressure fluid from the pipe line 15 to a plurality of longitudinally disposed inlet passages 45, 46 as is clearly shown in Fig. 4. These inlet passages (Fig. 6) preferably communicate with the cylinder 2 through a plurality of pairs of inlet passages 47, 48, the inlet ports 47 being adapted to communicate with the recess 35 when the piston is adjacent the rear end 45 of the cylinder and the inlet ports 48 being adapted to communicate with this same recess when the piston is adjacent the forward end of the cylinder, the ports 47 at this time being preferably closed. When the piston 50 is adjacent the rear end of the cylinder, as is

shown in Fig. 6, the fluid conducted through the inlet passages and inlet ports 47 to the recess 35, flows from this recess through a plurality of ports 49, 50, and 51 to a plurality of bypasses 52 which conduct the pressure fluid to the rear end of the cylinder behind the piston through ports 53, 54. During the rearward movement of the piston, pressure fluid will be admitted first through the port 49, then the port 50, and finally the port 51 70 and will enter the rear end of the cylinder, through the small port 53 and an annular recess 53' communicating therewith to cushion the rearward movement of the piston, and also through the larger port 54. If it is desired, part of these ports may be dispensed with, but in the present invention, the port 49 is provided to prevent stopping of the piston in the center of the cylinder, and the port 50 is provided to permit an earlier but smaller 75 flow of fluid than does the port 51 so that this fluid flow may pass rapidly to the rear end of the cylinder to build up sufficient pressure to properly cushion the piston on its rearward or return movement without short 80 stroking or excessive shock. As the piston moves forward, the ports 51, 50, 49 are successively cut off in the order named, and pressure fluid is admitted from the inlet ports 85 through ports 48 around the spooled section 90 of the piston to a second pair of bypasses 55 preferably disposed in alignment with the first bypasses but separated therefrom by webs 56. The fluid flow is first through a small port 57 and as the piston moves further 95 forward, through a larger port 58 to these return bypasses, and from thence through ports 59 and 60 to the forward end of the cylinder to drive the piston rearwardly. The port 57 is especially provided to permit a 100 small initial flow to the forward end of the cylinder through the port 60 and recess 60' communicating therewith and with the cylinder to cushion the forward movement of the piston should the striking head not be stopped 105 by a steel. In the preferred form shown, a port 60 is provided in only one of the return bypasses, but as is obvious, a similar port may be provided in the other bypasses. The ports 53 and 60, and grooves 53' and 60' also 110 serve to prevent the sticking of the piston in an end of the cylinder.

If desired, the ends of the cylinder or piston may be hollowed out to provide expansion space for the pressure fluid, but I preferably 115 use the hollow interior of the piston for a part of the steel rotating mechanism, to be herein-after described, and provide expansion space outside of the cylinder space 2, but in communication with this cylinder space, and also 120 with the bypasses. For this purpose I preferably use the longitudinal passageway 4 and divide this passageway into two expansion chambers 61, 62 by a web 63 which is preferably placed nearer the forward end of the cyl- 125

inder so that the expansion chamber 61 communicating with the rear end of the cylinder 2 is larger than the expansion chamber 62 communicating with the forward end of the cylinder 2. As is clearly shown in Fig. 5, the expansion chamber 61 communicates with one bypass 52 by a relatively large port 61', it being understood that the expansion chamber 62 communicates with the corresponding bypass 10 adjacent the front end of the cylinder, the latter not being shown since the construction is identical with that disclosed in Fig. 5. It will be noted that I have shown but one set of expansion chambers surrounding but one rod 15 20 and communicating with but one pair of bypasses, but it will be obvious that if desired, a similar set of expansion chambers may be formed adjacent the other side rod 21 in communication with the other pair of bypasses. 25 It will further be obvious that if it is desired, these expansion chambers may be formed elsewhere in the walls of the cylinder or on members formed on the cylinder instead of around a tie rod as shown, but I preferably use this construction in order to lighten the machine, to render it more compact, reduce the number of pieces required, and reduce the cost of manufacture.

After the pressure fluid from the expansion chambers and bypasses has been used to drive the piston in one direction or the other, it may be exhausted to the atmosphere through suitable ports and for this purpose, a port 64 communicating with an exhaust passage 65 is formed near the rear end of the cylinder, and a port 66 is provided for exhausting the pressure fluid from the front end of the cylinder, the exhaust from the latter end of the cylinder being directed forwardly away from the operator by a depending flange 67. In order to increase the efficiency of the motor, I preferably provide an exhaust valve for the rear end of the cylinder to permit the placing of the port 64 near the center of the cylinder and so to delay the moment of exhaust as long as possible and thereby permit a greater expansion of the fluid in this end of the cylinder without, however, causing short stroking by excessive cushioning. As is obvious, a similar exhaust valve may be provided to control the exhaust port adjacent the front end of the cylinder. In the form of my invention shown this exhaust valve is preferably carried in a boss 68 herein shown as formed integral with the cylinder 1, a sleeve 69 being provided to close the open end of a chamber formed in this boss in which chamber the stepped exhaust valve 70 is mounted. In the construction shown in the present drawings, the sleeve, valve, and boss are axially apertured to receive the nut 32 which coacts with the threaded rod 31 to feed the cylinder toward or away from the work, but this placing of the exhaust valve is not a part of the present invention, the same being the invention of one Elmer G. Gartin

and claimed by him in U. S. Patent No. 1,568,802 dated October 27, 1925. The exhaust valve 70 is preferably provided with opposite faces 71 and 72 on which the pressure fluid acts to throw the valve in one direction or the other to permit or check the exhausting of fluid from the rear end of the cylinder, the valve in the position shown in Fig. 1 being in its forward position to stop the flow of exhaust fluid to the atmosphere by the contact of the valve with an annular seat 73 formed on the boss 68. The pressure fluid which acts on the annular surface 71 to force the valve against the seat 73 is admitted from the rear end of the cylinder through a single or a plurality of ports 74 and a passage or passages 75 to an annular chamber 76, it being understood that the pressure admitted by these ports and passages to the face 71 is at its greatest when the recess 35 is in communication with the bypass 52, and is at its lowest when the pressure fluid is cut off from this end of the cylinder and the piston is adjacent the front end of the cylinder with the exhaust port 64 uncovered. The valve 70 is thrown in the opposite direction when the piston moves far enough forward to permit pressure fluid from the recess 35 to enter a port 77, flow through a longitudinally disposed passageway 78, and pass through a port 79 to an annular recess 80 where it acts on the surface 72 of the valve, the pressure of the fluid acting on the opposite surface 71, at this time, being relatively small. As the piston again moves rearwardly, the passage 78 and with it the cooperating ports in the annular chamber 80, are exhausted through a second port 84 opening into the passage 78 preferably in advance of the port 77. When the parts are in the position shown in Fig. 1, pressure fluid admitted to the rear end of the cylinder space 2 will act against the rear end of the piston until the exhaust port 64 opens. At this instant the port 77 is opened, the exhaust valve is thrown rearwardly, and the secondary exhaust port 81 is opened permitting a flow of fluid through this port, annular passageways 82, 83 to the exhaust passage 65. As the piston starts its rearward movement, a pressure is built up in the rear end of the cylinder and on the face 71 of the exhaust valve, and at the same time, the pressure on the face 72 is exhausted so that this valve is thrown forward and rests against the seat 73 until the port 77 is again placed in communication with the recess 35. It will thus be seen that I have provided a plurality of inlet passages which admit pressure fluid to the cylinder on opposite sides thereof to balance the action of the pressure fluid on the piston and prevent the binding of the latter against the cylinder walls, that I have provided a plurality of expansion chambers communicating with the ends of the cylinders to provide a proper quantity of pressure fluid to drive the piston in either direc-

tion, and that I have provided a simple and efficient exhaust valve whereby a very efficient operation of the motor is obtained.

If desired, the motor may be used for operating on solid drill steels and in that form, means need not be provided for supplying a cleansing fluid to the steel bit. Since it is highly desirable to have a cleansing fluid controlling means for use with hollow steels, I provide means preferably controlled by the handle 14' which controls the flow of pressure fluid to the motor, for admitting a cleansing fluid to the axial bore of a hollow drill steel for cleansing purposes. For this purpose I have shown the water tube 17 connected to the boss 16 and having communication therewith through a passageway 85 which conducts the water or other liquid to an annular chamber 86 formed preferably around a gland plug 87 which is shown as threaded into the head block 13. From this annular passage the water is conducted by a passage 88 to a port 89 in the sleeve 90, in which sleeve the valve 14 is adapted to turn, the sleeve being preferably held against rotation. Communicating also with the port 89 is a passageway or groove 91 formed longitudinally in the sleeve 90 and communicating adjacent its opposite end with the radial port 92 formed in the sleeve, which port is adapted to communicate with a port 93 (Fig. 8) formed in a wall of the conical valve 13 in such a manner that in a given position of this valve 14, air will be admitted through these ports and passages in the reverse order named to the port 89. Formed also in the valve 14 and preferably in the same transverse plane with the passageway 88 is a circumferential groove 94 which is adapted to communicate with the port 89 and also a port 95 formed in the sleeve in spaced relation to the port 89 to conduct water from the water tube or air admitted from the valve to a passageway 96, herein shown as formed parallel to the passageway 88. The flow of pressure fluid through the passage 96 is conducted through an angular passage 97 to an aperture 98 in the gland plug 87, from whence it passes through a tube 99 securely held by the plug in the head block 13 through the piston to the hole 11 in the drill steel. The ports and passages in the valve 14 and the cooperating sleeve 90 are so formed that when the controlling handle 14' is in the position indicated by the line X, all the ports are closed and the motor is wholly inoperative. As the controlling handle 14' is moved counterclockwise (see Fig. 3) air is first admitted through the tube 99 to the drill steel to clear the tube, drill steel, and bit of any particles which might otherwise block or hinder a flow of liquid. Upon a further rotation of the controlling handle in a counterclockwise direction, the air flow to the tube is cut off and water is admitted to the tube to wash the cuttings out of the hole. As the valve is still fur-

ther rotated in the same direction, the port 41 (Fig. 4) is placed in communication with the passageway 43 and a flow of pressure fluid is admitted to but one inlet to operate the motor relatively slowly. When the controlling handle 14' is moved to the position indicated by the line Y (Fig. 3), pressure fluid is admitted to both inlet passageways, the liquid being still admitted to the drill steel through the tube 99, and the motor is operated under full pressure, the cuttings made by the steel being washed away by the liquid. To shut off the motor, the handle 14' is rotated in a clockwise direction (see Fig. 3) and the ports and passages are controlled in a reverse manner, the final flow through the hole 11 in the drill steel being a puff of pressure fluid to clean the liquid from the steel. If desired, the port 93 may be elongated to permit a mixture of air and water to flow to the steel, but I preferably use a small port as I find that the liquid flow is sufficient to remove the cuttings during normal cutting operations.

In the form of my improved motor shown herein, I preferably provide means for rotating the drill steel and preferably to connect the chuck which receives the drill steel to the piston 34 so that the latter actuates the rotating mechanism during the rearward movement of the piston. In order to keep the motor small, compact, and light and to decrease the weight of the piston so as to increase the efficiency of the motor, the piston is preferably hollowed out throughout the greater part of its length to provide a stepped bore in which certain of the parts of the rotating mechanism are placed. In the form of my improvement shown, straight grooves 100 are formed on a forwardly extending sleeve 101 preferably formed integral with the top plate 12, these grooves coacting with straight longitudinally extending feathers 102 formed in a sleeve or retaining bushing 103 attached to the piston as by a threaded connection therewith, although as is obvious, other means may be used for retaining this bushing in the piston. In order that the pressure fluid may flow freely past the feathers 102 to act on the rear surfaces of the piston head, I also form these feathers with concaved outer surfaces 102' as is clearly shown in Fig. 9. These coacting parts keep the piston from an angular movement relative to the cylinder when the motor is being operated. The reciprocating movement of the piston is preferably utilized to rotate the rotating mechanism by means of a rifle nut 104 carrying spiral rifle grooves 105, this nut being shown as threaded into the smaller and inner bore of the stepped piston until a flange 106 formed on the nut contacts with an annular shoulder adjacent the smaller bore of the piston. Cooperating with these rifle grooves are spirally formed rifle feathers 107 formed on a non-reciprocating but angularly movable rifle bar 108, the

latter having a guiding and supporting section 109 herein shown as formed adjacent the feathers 107. This rifle bar is preferably formed with an enlarged hollow head 110 which surrounds an inwardly projecting boss on the head block 13 into which the gland plug 87 is screwed, and if desired, there may be formed in the circumference in this head 110, a plurality of chambers 111 adapted to 5 retain grease for lubricating the parts of the rotating mechanism (Fig. 4). Mounted also in the periphery of the hollow head 110 of the rifle bar are a plurality of pawls 112 which are normally pressed outward by pawl 10 pins 113 and pawl springs 114. These pawls 112 are adapted to engage internal ratchet teeth 115 formed on a ratchet ring 116, which is preferably mounted concentric with the rifle bar and which also carries on its outer 15 circumference a plurality of gear teeth 117. This ratchet ring is held in concentric relation to the rifle bar and the cylinder by a forwardly extending, reduced sleeve 118 which receives the guiding portion 109 of 20 the rifle bar and is in turn received by the axial sleeve 101 carried by the top plate 12. The rotating parts mounted coaxially with the cylinder are thus retained in their proper relationships to the cylinder and ample bearing space is provided for the rifle bar and the 25 ratchet ring.

The gear teeth 117 coact with and drive a small pinion 119 preferably formed integral with a hollow shaft 120 herein shown as rotatively mounted on a bushing 121 which surrounds the side rod 21, the shaft 120 carrying at its forward end clutch teeth 122 adapted to coact with clutch teeth 123 formed on a longer shaft 124 which is also mounted concentric to the guide rod 21. The rotative movement imparted to the shaft 124 is preferably transferred to the chuck 7 by a small pinion 125 formed on the shaft 124 and external teeth 126 formed on the rear enlarged 40 portion of the chuck. When the piston moves forward, the straight longitudinal grooves and feathers 100, 102 keep the piston from rotating and the spiral rifle grooves and feathers 105, 107 rotate the pawl carrier in one direction, the pawls during this rotation sliding over the ratchet teeth 115. However, when the piston moves rearwardly, these rifle grooves and feathers rotate the pawl carrier in the opposite direction, and the pawls engage the ratchet teeth which transfer the rotative movement of the rifle bar to the ratchet ring which in turn rotates the chuck by means of the pinions and countershaft above described. The rotative movement of the 45 chuck may be transferred to the steel and the drill steel may be detachably secured in the chuck in a variety of ways, but in the form presented, the steel 9 and the lugs 10 formed thereon are adapted to be passed through an opening 128 in the chuck ring 8 into a space

between the chuck bushing 6' and the chuck ring, the latter having formed thereon a plurality of rearwardly extending lugs 129 (Fig. 13) by means of which the chuck ring is caused to rotate with the chuck 7. As is best 50 shown in Fig. 13, the space between the chuck bushing and the chuck ring is formed with two oppositely disposed lug receiving chambers 130 having a plurality of shoulders 131 adapted to engage the lugs 10, when the chuck is rotated, to transfer the rotative movement of the chuck to the steel. If it is desired to remove the steel from the chuck, the steel is given a partial rotation in advance of the chuck until the lugs 10 are aligned with the 55 opening formed in the retaining ring 8, when the steel may easily be withdrawn from the chuck. This construction is adapted to receive a lugged steel of the type shown but it is to be understood that the openings formed in the chuck and chuck ring may be varied in accordance with the style of steel used as for instance, these openings may be formed hexagonal to receive a hexagonal steel of a 60 type now commonly used.

Under certain conditions as when starting a hole on an inclined surface, it may be desirable to operate the motor without rotating the steel and for the purpose of disconnecting the piston or certain parts connected therewith from the chuck so that the steel will not be rotated, I preferably provide a clutch mechanism which may be of any type desired, and I have illustrated one form which this clutch and clutch controlling mechanism may assume in Fig. 11. For this purpose, I have shown a boss 132 formed on the side of the cylinder and carrying a shipper yoke 133 adapted to coact with a groove formed on the sleeve or hollow shaft 120 in a well known 65 manner, the shipper actuated by a shipper rod 134 and a controlling handle 135 attached thereto. The clutch teeth 122 and 123 are engaged or disengaged by reciprocating the shipper yoke and the shaft 120. In use the motor may vibrate and tend to throw this shaft forward into engagement with the shaft 124 or backward to release this shaft, and to prevent this, I have shown a pin 136 normally pressed into contact with the control rod 134 by a spring 137, the latter being retained under compression by a cap 138. This pin preferably coacts with a plurality of grooves 139, 140 formed on the shipper rod to hold this rod against reciprocation 70 until it is actuated by the operator to throw the clutch.

Practice has shown that when the motor is driving the steel into hard material, the teeth 122 and 123 may become locked together so 75 that it will be difficult to throw these teeth out of engagement by a movement of the controlling rod and to overcome this difficulty, I have shown in Fig. 15 a modified form of clutch controlling mechanism by means of 80

which these teeth may be more easily disengaged. In this form of clutch controlling mechanism, I have shown a shipper yoke 141 and a shipper rod 142 threaded as shown at 5 143 into the shipper yoke, the rod 142 being rotated by the operator by means of a handle 144 attached to the outer end of the rod. This rod is preferably mounted in bearings 145, 146 and a spring 147 is provided to hold 10 the rod in its proper position, and to prevent the jumping or rattling of the clutch mechanism during the operation of the motor.

Various known means may be utilized for lubricating the different parts of the motor, 15 but I preferably provide in the longitudinal chamber 3 between the shaft 124 and the outer wall of the motor a lubricating reservoir which is at all times in communication with the various parts of the motor which require lubrication. A filling port 148 (Fig. 10) is provided through which oil or grease may be placed in this oil reservoir and a cap or plug 149 is also provided for closing this port. The shaft 124 is shown as being provided 20 with a hole 150 through which grease may flow to lubricate the bearing or side rod 21 on which this shaft rotates. A groove is preferably formed in the engaging parts of the shafts 120, 124 to permit a flow of grease to 25 the rotating parts in the rear end of the cylinder although if desired, this groove may be dispensed with and sufficient clearance may be provided around the shafts and the clutch teeth to permit the lubricant to pass. 30 By this improved lubricating means, the weight of the motor is not increased by providing additional parts to receive the lubricant supply, and the lubricant reservoir formed about the tie rod 21 is always in free 35 communication with all the moving parts at both ends of the motor, and these parts at all times receive an adequate supply of lubricant. 40

It will thus be seen that I have provided a novel, light, compact, efficient, and powerful 45 motor having an improved piston reciprocating means, an improved exhaust valve for controlling the exhaust from the cylinder, and an improved steel rotating mechanism, which is always adequately lubricated, which 50 does not take up additional space on the ends of the motor, and which may be thrown into or out of operation at the will of the operator. It will further be noted that I have provided 55 an improved lubricating means which does not add to the weight of the motor, which will contain a sufficient supply of lubricant for a long period of operation, and which will efficiently lubricate all of the working parts. It will be noted that another feature 60 of the invention is the control of the flow of pressure fluid to the motor and the flow of cleansing fluid to the drill bit to admit the flow of these fluids to the proper parts in their proper sequence, and that this flow is

so controlled that the air is admitted to the 65 steel before and after the flow of cleansing liquid to properly clear the steel and tube of obstructions.

While I have in this application specifically described two embodiments which my invention may assume in practice, it is to be understood that these forms are shown for illustrative purposes only and that the invention may be modified and embodied in various other forms without departing from 75 its spirit or the scope of the appended claims.

What I claim as new and desire to secure by Letters Patent is:

1. In a drilling mechanism, a drilling motor comprising a cylinder and a hollow piston reciprocable therein, a tool actuated by said piston, and rotation mechanism for said tool comprising relatively movable concentrically arranged members extending into the interior of and connected to said piston, 80 one of said members controlling said piston for predetermined movement during reciprocation thereof, and operative driving connections between the other of said members and said tool.

2. In a drilling mechanism, a drilling motor comprising a cylinder and a hollow piston movable therein, a tool actuated by said piston, a tool receiving chuck, and rotation mechanism for said chuck operated by said piston including a member cooperating with the interior of said piston for preventing rotation thereof, a member having spiral lugs and arranged concentrically with said member and extending into the interior of the rear end of the piston, said members being relatively movable, means carried by the piston having spiral grooves for cooperating with the spiral lugs on said latter member, operative driving connections between said last mentioned member and said tool receiving chuck, and means for interrupting rotation of said chuck while relative movement between said members continues.

3. In a drilling mechanism, a drilling motor comprising a cylinder and a hollow piston reciprocable therein, a tool actuated by said piston, a tool receiving chuck, and rotation means for said chuck including a member extending forwardly from the rear end of said cylinder and having straight grooves cooperating with said piston for preventing relative rotation between the latter and said cylinder, a member arranged concentrically with said member and extending forwardly from the rear end of the cylinder and having spiral grooves cooperating with said piston and adapted to be rotated by the latter, and driving connections between said rotatable member and said tool receiving 110 chuck.

In testimony whereof I affix my signature.
GEORGE H. GILMAN.
